UNITED STATES PATENT OFFICE

2,587,974

COMBINATION VAPORIZER AND BLOWER

George P. Daiger, Canton, Ohio, assignor to The Hoover Company, North Canton, Ohio, a corporation of Ohio

Application February 5, 1948, Serial No. 6,409

3 Claims. (Cl. 21—127)

1

The present invention relates to suction cleaners in general and more particularly to a new and novel combination vaporizer and blower attachment for suction cleaners, preferably of the ambulant type.

The present invention also relates to moth-proofing fabric materials, such as clothes. By moth-proofing is meant treatment, for example with the gas of para-dichlorobenzol or para-dibromobenzol, to protect against moths. The invention also relates to disinfecting or air conditioning or other treatments of articles wherein a gas such as air laden with the vapor of an insecticide or perfume is used. Furthermore, the invention relates to coupling means for connecting a hose to a vaporizing attachment for a suction cleaner.

It is therefore an object of the present invention to provide an attachment for a suction cleaner whereby the exhaust therefrom may be utilized for vaporizing pulverized crystals and conveying the fumes to rugs, upholstered furniture, drapes, clothing, closets, baseboard and floor cracks.

It is another object of the invention to provide an attachment for a suction cleaner to utilize the fumes therefrom as vaporized in the attachment for purifying the air and for disinfecting sick rooms.

Furthermore, it is an object of the present invention to provide a simple vaporizer attachment which may be readily attached to or detached from the suction cleaner exhaust outlet, for carrying out any and all of the above objects or which while still in its attached position may be rendered inoperative as an insecticide or disinfectant vaporizer in order to permit the normal operation of the suction cleaner as a blower for cleaning by blowing.

These and other objects may be attained by providing in combination with a power driven fan, an exhaust outlet therefor together with a hose and a nozzle of a suction cleaner, a vaporizer and blower attachment which may be stated in general terms as including an attachment provided with a tube connection for cleaning by blowing, a tube connection for moth-proofing together with means for mounting a conventional glass jar containing a material which is vaporized when supported on the attachment and with the glass container removed the attachment is adapted for cleaning by blowing.

These and other more specific objects will appear upon reading the following specification and claims and upon considering in connection there-

2

with the attached drawings to which they relate.

Figure 1 is an assembly view showing the invention as applied to the exhaust outlet of an ambulant type floor cleaner and adapted for vaporizing a material for moth-proofing;

Figure 2 is an enlarged view of the vaporizer attachment mounted on the exhaust outlet of a suction cleaner, adapted for cleaning by blowing; Figure 3 is an exploded isometric view illustrating the combination vaporizer and blower attachment with the container for the vaporizable material detached;

Figure 4 is a rear view in elevation of the attachment illustrating the various means for securing the vaporizer attachment and blower to the exhaust outlet of various types of commercial cleaners; and,

Figure 5 is a vertical sectional view taken along the line 5—5 of Figure 4, illustrating the flow of air through the vaporizer attachment as it is adapted for vaporizing a material for moth-proofing, disinfecting or perfuming.

Referring to Figure 1, a conventional suction cleaner 10 is shown which includes the usual motor driven fan, suction nozzle and agitator therefor, wheel supported and adapted to be propelled by the conventional handle to which a dirt bag is usually attached but for the purpose of utilizing the combination vaporizer and blower attachment 11 of this invention the bag has been detached for affixing the attachment to the exhaust outlet of the suction cleaner. In order to describe the operation of this invention, the attachment 11 has been illustrated in conjunction with a conventional garment bag 12. The garment bag is connected with the vaporizer attachment 11 by a conventional wand construction 13, hose 14 and a cleaning tool hose connection 15.

The combination vaporizer and blower attachment 11 is provided with a mounting bracket 16 having latching means 17 and 18 adapted to be attached to the suction cleaner by latching means 19 and 20 shown in Figure 1. In the suction cleaner illustrated in Figure 2, the combination vaporizer and blower attachment 11 is affixed to the exhaust outlet of the suction cleaner 10 by laterally positioned ears 21 adapted to be secured to the suction cleaner by clamping means 22 shown in Figure 2. It is thus obvious that with this construction, the combination vaporizer and blower attachment is adapted for mounting on existing conventional cleaners.

The mounting bracket 16 shown in Figure 5 is secured by suitable means 22 to a molded plastic housing 23 forming the combination va-

porizer and blower construction. A screen 24 is positioned between the opening of the bracket 16 and the opening 25 of the attachment in order to prevent crystals of vaporizable material positioned within a glass jar 26 from discharging into the exhaust of the suction cleaner in the mounted position thereon as illustrated in Figure 1. The jar 26 is detachably mounted in an enlarged opening or jar socket 27 by threads 28 which receive threads 29 formed on the jar. It is within the scope of the invention that standard glass jars may be adapted for use with the combination vaporizer and blower attachment as are commercially available although it is obvious that other forms of jars and securing means thereon may be utilized.

Axially located in the housing 23 with respect to the axis of the jar 26 is a tube 30 which serves to discharge the exhaust air from the suction cleaner into the jar, as illustrated by the arrows in Figure 5 with the jar in position, and the tube 30 also serves as a wand connection when the apparatus is used solely for cleaning by blowing, as illustrated in Figure 2. Referring to Figure 2 when the cleaner is utilized for blowing, the wand 13 is connected to the tube 30 by an umbrella type latch mechanism 31 provided with a locking detent 32 adapted to engage a groove 33 machined or molded within the tube 30. This particular form of connection permits the ready attaching and detaching of the wand to the combination vaporizer and blower attachment upon the actuation of a thumb control button 34 also permits swiveling of the wand within the tube 30. The latch mechanism which is of standard construction is mounted within a dog-house 35 to prevent excess leakage within the wand to reduce the efficiency of operation.

When utilizing the apparatus for vaporizing a substance for moth-proofing and the like as shown in Figure 5, the flow of air follows that of the arrows through a tube 36 to which the wand 13 is adapted to be connected in the manner as described with reference to Figure 2. The tube 36 is molded integrally with the housing 23 and is connected by a passageway 38 extending laterally and downwardly as illustrated in Figure 4 to an annular chamber 37 formed by the tube 30 and the housing 23. The rear end of the passageway 38 is provided with a detachable cover plate 39 preferably formed of sheet metal and complementally formed with respect to the passageway 38 to form a closure for the rear end of the tube connection 36, as illustrated in Figure 5, and to permit the mounting of a screen 40 across the passageway 38. The cover plate 39 is affixed to the housing 23 by securing means 41. The screen 40 prevents the crystals within the jar 26 from discharging through the tube 36 into the dusting tool hose 14 thus permitting efficient use of the vaporizable material.

It is thus obvious that there has been disclosed a simple combination vaporizer and blower apparatus which is adapted for cleaning by blowing as illustrated in Figure 2 by mounting the dusting tool hose within the tube 30 and may be readily converted to a vaporizing apparatus by affixing the jar 26 containing the vaporizable material to the apparatus as illustrated in Figure 1 and attaching the wand as illustrated in Figures 1 and 5 to the tube 36 to discharge the air conditioned by vaporizable material either for moth-proofing, deodorizing, disinfecting, and the like.

With the various parts assembled as shown in Figure 1, and with vaporizable reagent crystals in the jar 26, the suction cleaner may be operated for moth-proofing the garments within the bag 12 upon discharge of the air conditioned vapor through the hose 14. Referring to Figure 5, the flow of air from the suction cleaner is upwardly through the tube 30 and through the vaporizable material within the jar 26 and downwardly through the annular passageway 37 to be discharged through the passageway 38 and finally through the tube 36 to which the wand 13 and the hose 14 are connected to discharge the fumes of the vaporizable material for disinfecting, fumigating, air purifying and the like.

If it is desired to actuate the combination vaporizer and blower attachment as a blower, the operator simply detaches the wand 13 from the apparatus, as illustrated in Figures 1 and 5, by depressing the button 34. The operator then re-embeds the wand within the tube 30 as illustrated in Figure 2 after detaching the jar 26 from the position as shown in Figure 1. Referring to Figure 2, the exhaust air from the suction cleaner then discharges directly through the tube 30 through the wand 13 and hose 14 and through the various tools which may be connected to the cleaner tool hose connection 15 for cleaning by blowing. It is also obvious that with this attachment the suction cleaner may be pulled along through the connection of the hose with the handle of the suction cleaner in its vertical storage position as shown in Figure 1.

After the operator has utilized the combination vaporizer and blower attachment either for cleaning by blowing or for moth-proofing, disinfecting and the like operation, the suction cleaner may be restored to its original condition by releasing the clamping means 20 of Figure 1 or 22 shown in Figure 2 permitting detachment of the apparatus, whereupon the dirt filtering bag may be replaced in the reverse order. The cleaner is then ready for its normal operation as a typical ambulant type floor cleaner.

It is to be understood that whereas there has been described and illustrated a practical and operable combination vaporizing and blower attachment for a suction cleaner as applied to the exhaust outlet of an ambulant type suction cleaner, nevertheless many changes may be made in the size, shape, number and disposition of parts without departing from the spirit of this invention.

What is claimed is:

1. An accessory for treating the air discharged from a suction cleaner and comprising a body, means for connecting said body to the air discharge outlet of a suction cleaner, means defining a conduit in said body conveying the untreated air from the suction cleaner discharge outlet and having an outlet for the untreated air, a container for vaporizable crystals having a mouth and being otherwise closed to treat the air, means removably attaching said container to said body, said container when attached to said body receiving said conduit outlet telescoped within said container mouth to convey the untreated air to said container of crystals to treat the air, said conduit outlet being of less diameter than said container mouth to form therewith an annular outlet for the treated air, and means in said body cooperating with the exterior of said conduit to form an annular passageway communicating with said annular treated air outlet to discharge the treated air from said body.

2. An accessory as described in claim 1, and connecting means in said conduit for attaching a cleaner hose to said conduit outlet to convey the untreated air from said body when said container is removed from said body, said container when removed from said body uncovering said conduit outlet for said attachment of the cleaner hose.

3. An accessory for treating the air discharged from a suction cleaner and comprising a body, 10 means connecting said body to the cleaner air discharge outlet, means defining a conduit in said body conveying the untreated air from the suction cleaner and having an outlet for the untreated air, connecting means for removably attaching a cleaner hose to said conduit outlet to convey the untreated air from said body, a container for vaporizable crystals having a mouth and being otherwise closed to treat the air, means removably attaching said container to said body, 20 said container when attached to said body receiving said conduit outlet telescoped within said cleaner mouth to receive the untreated air and

prevent said attachment of said cleaner hose to said conduit outlet, said conduit outlet being of less diameter than said container mouth to form therewith an outlet for the treated air, and means in said body forming a passageway for conveying the treated air from said treated air outlet to the exterior of said body.

GEORGE P. DAIGER.
